PRESSER MECHANISMS FOR SEWING MACHINES

David B. Scott, Plainfield, and Richard W. Schmutzler, South Plainfield, N. J., assignors to The Singer Manufacturing Company, Elizabeth, N. J., a corporation of New Jersey

Application May 26, 1954, Serial No. 432,404

3 Claims. (Cl. 112—237)

The present invention relates to sewing machines and has as a primary object to provide an improved presser mechanism for sewing machines. More particularly, it is an object of this invention to provide an improved means for relieving the bias-pressure on the presser mechanism while the needle is in the work. This mechanism is designed to permit the work to be turned about the needle as an axis, which is desirable in sewing around tight curves such as about the ends of the fingers of gloves.

Having in mind the above and other objects that will be evident from an understanding of this disclosure, the invention comprises the devices, combinations and arrangements of parts as illustrated in the presently preferred embodiment of the invention which is hereinafter set forth in such detail as to enable those skilled in the art readily to understand the function, operation, construction and advantages of it when read in conjunction with the accompanying drawings in which:

Fig. 1 is a fragmentary head end elevation view of a sewing machine embodying the invention, with the face-plate removed to illustrate more clearly the underlying mechanism, and with the bed mechanism broken away.

Fig. 2 is a fragmentary rear side elevation view of the head end of the machine illustrated in Fig. 1.

Fig. 3 is a fragmentary top plan view of the head end of the machine of Fig. 1.

Fig. 4 is a fragmentary sectional view taken substantially on the line 4—4 of Fig. 1.

The present invention is herein illustrated as embodied in a sewing machine of the two-thread chain stitch type such as illustrated in the patent of Clayton, No. 2,345,327, to which patent reference may be had, if desired, for a more complete description of the machine. The machine is herein illustrated and described only insofar as is necessary for a complete understanding of the invention.

With reference to the drawings, the machine comprises a frame having a bed 1, a standard 2 rising from the bed, and a bracket-arm 3 carried by the standard 2 and overhanging the bed 1, the bracket-arm terminating in a head 4. The stitching mechanism of the machine includes a needle-bar 5 slidably mounted for longitudinal reciprocation in bearings 6 in the head 4 and carrying a needle 7 at its lower end. The needle-bar is reciprocated in the usual manner by a counter-balanced crank 8 which is secured to the end of a rotary main-shaft 9 journaled longitudinally of the bracket-arm 3, which crank is provided with a crank-pin 10 connected by a link 11 with a collar 12 secured to the needle-bar.

The feeding mechanism of the sewing machine includes a feed-dog 13 that acts through slots in a throat-plate 14 carried by the bed 1. Acting in cooperation with the feed-dog 13 is a presser mechanism comprising a presser-foot 15 secured to the lower end of a short hollow presser-bar 16 mounted for sliding movement in an elongated bearing bushing 17 in the head 4. The presser-bar 16 has secured thereon at the upper end a collar 18 having

2

an arm 19 that normally overhangs a finger 20 of a link 21 which is pivotally carried by a presser-lifter lever 22, which is in turn pivoted to the bracket-arm by a pivot-screw 23. The presser-bar 16 may be lifted in the usual manner by pivoting the lever 22 about its pivot 23.

A rod 24 slidably extends into the hollow of the presser-bar 16 and upwardly through an aperture 25 in the upper wall of the head 4. A coil compression spring 26 encircles the rod 24, which spring abuts at its lower end against the upper surface of the collar 18 and thereby urges the presser-bar 16 downwardly. At its upper end the spring 26 abuts against a collar 27 fast on the rod 24. The rod 24 loosely extends through a bushing 28 threaded into the aperture 25 and locked therein by a lock-nut 29 threaded onto the same.

Upon the rear of the head 4 and the adjacent portion of the bracket-arm 3 there is a boss 30 in which is journaled for oscillation a countershaft 31 that is arranged parallel to the main-shaft 9. Oscillation is imparted to the countershaft 31 upon rotation of the main-shaft 9 by an adjustable eccentric 32 fixed on the main-shaft and having the eccentric portion 33 thereof embraced by the strap-portion 34 of a pitman 35, the free end of which pitman is pivotally connected, as by a pin 36, to the end of a crank 37 fixed to the countershaft 31. Fixed to the other end of the countershaft 31, as by a pin 38, is a second crank-arm 39 the free end of which is pivotally connected by a pivot-screw 40 to the lower arm 41 of a two-arm bracket 42. The bracket 42 also includes an upper arm 43 which is adjustably secured to the arm 41 by screws 44 that extend through an elongated slot 45 in the arm 41 and are threaded into the arm 43. The arm 43 is formed with an angularly bent upper portion 46 that overlies the end of the rod 24 projecting from the head 4 and serves as an abutment for the rod 24 to hold the same depressed against the action of spring 26. A boss 47 is provided on the underside of the portion 46 of arm 43, the face of which boss is, as best seen in Fig. 4, made concave to receive the upper end of the rod 24.

It will be apparent that upon oscillation of the countershaft 31, the crank-arm 39 will be oscillated, which will, in turn, depress and relax the bracket 42. Since the arm portion 46 of the bracket 42 constitutes the upper abutment of the rod 24, depressing the bracket 42 will depress the collar 27 which collar is the upper abutment of the spring 26. As will be evident, when the collar 27 is depressed, the spring 26 will be compressed which increases the spring pressure upon the presser-bar 16, and when it is relaxed, the spring will be permitted to expand which reduces the spring pressure upon the presser-bar 16. The movement of the bracket 42 is made such that when the rod 24 is depressed, there is a normal working pressure on the presser-bar 16, and when it is relaxed, there is a greatly reduced pressure on the same which will permit ready manipulation of the work. The eccentric 32 is timed so that the rod 24 is depressed and the normal pressure is on the presser-bar while the needle is out of the work and the feeding mechanism is operating, and so that the pressure is reduced while the needle is in the work to permit use of the needle as a pivot axis for turning the work about sharp corners.

Having thus described the nature of the invention, what we claim herein is:

1. In a sewing machine having a bed and a bracket-arm terminating in a head and overhanging said bed cooperating stitching mechanism carried by said head and bed, a rotary shaft journaled longitudinally of said bracket-arm, operative connections between said rotary shaft and said stitching mechanism for actuating the latter upon rotation of said shaft, a presser-bar mounted in said head for sliding movements, a rod arranged coaxially of and having the one end thereof telescoping with said presser-
- 65
- 70

bar, a collar secured on said rod, a coil compression
spring encircling said rod and acting between said collar
and said presser-bar for urging said presser-bar toward
said bed, an abutment for said rod to hold the same de-
pressed against the action of said spring, and means for
varying the position of said abutment in timed relation
to the actuation of said stitching mechanism comprising
a countershaft arranged parallel to said rotary shaft and
journalized in said bracket-arm for oscillation, operative
connections between said rotary shaft and said counter-
shaft for imparting oscillation to the latter upon rotation
of the former, a crank-arm fixed to said countershaft,
and operative connections between the free end of said
crank and said abutment for moving the abutment axially
of said rod upon oscillation of said crank-arm.

2. In a sewing machine having a bed and a bracket-
arm terminating in a head and overhanging said bed, a
presser-bar mounted in said head for vertical sliding
movements, a rod arranged coaxially of and having the
lower end thereof telescoping within said presser-bar, a
collar secured on said rod, a coil compression spring
encircling said rod and acting between said collar and
the upper end of said presser-bar for urging said presser-
bar downwardly toward said bed, an abutment for said
rod to hold the same depressed against the action of said
spring, said abutment comprising a bracket having an
arm with a portion overlying the upper end of said rod,

and means for varying the position of said abutment
comprising a rotary shaft journalized longitudinally of said
bracket-arm, a countershaft journalized in said bracket-
arm and arranged parallel to said rotary shaft, an eccen-
tric on said rotary shaft, a pitman having a strap portion
embracing said eccentric, a first crank-arm secured to
said countershaft, the free ends of said pitman and first
crank-arm being pivotally interconnected to impart oscil-
lation to said countershaft upon rotation of said rotary
5 shaft, and a second crank-arm secured to said counter-
shaft and having the free end thereof pivotally connected
to said bracket for moving the abutment axially of said
rod upon oscillation of said countershaft and in timed
relation to the rotation of said rotary shaft.

10 15 3. The combination set forth in claim 2 in which said
bracket comprises a pair of adjustably interconnected
arms for varying the position of said abutment.
